UNITED STATES PATENT OFFICE.

JOHN C. COLE, OF SPRINGFIELD, MASSACHUSETTS, ASSIGNOR TO THE DREADNAUGHT TIRE & RUBBER COMPANY, OF ORANGEVILLE, MARYLAND, A CORPORATION OF MARYLAND.

DESIGN FOR A PNEUMATIC TIRE.

52.054.

Specification for Design.

Patented May 28, 1918.

Application filed March 12, 1918. Serial No. 222,040. Term of patent 14 years.

To all whom it may concern:

Be it known that I, JOHN C. COLE, a citizen of the United States, residing at Springfield, in the county of Hampden, State of Massachusetts, have invented a new, original, and ornamental Design for Pneumatic Tires, of which the following is a specification, reference being had to the accompanying drawing, forming part thereof.

The figure represents a perspective view

of a portion or a section of a tire embodying the design.

I claim:

The ornamental design for a pneumatic tire, as shown.

The foregoing specification signed at Springfield, Mass., this first day of March, 1918.

JOHN C. COLE.
